LOCK

Norman B. Hurd, New Britain, Conn., assignor to
The American Hardware Corporation, New
Britain, Conn., a corporation of Connecticut

Application December 15, 1928, Serial No. 326,206

17 Claims. (Cl. 70—91)

This invention relates to locks and latches, particularly of the type in which a key mechanism, such as a pin cylinder lock, is used within one of the knobs to turn a lock and/or latch operating spindle, which passes inwardly through the knob shank. It is of further importance in connection with such locks and latches as embody mechanism mounted on and cooperating with the knob shank. The invention primarily resides in a construction which permits the cylinder lock mechanism contained within the knob to be quickly and easily removed by a mechanic, not necessarily skilled in the lock art, so that another cylinder, adapted to be operated by a different key, may be substituted. In most locks of the type referred to, to substitute one cylinder for another within the knob mechanism involves not only considerable labor, but also requires a skilled mechanic. My present invention is of importance in that it reduces substantially the time required to change the cylinder, and also obviates the necessity of employing a lock expert for that purpose. The purpose of this invention may be better understood when it is appreciated that in large apartments and office buildings, wherein a great number of such locks are employed, the occupants of the apartments and offices are frequently changed, so that it becomes necessary to provide each new tenant with a different key. The present invention permits this to be easily and quickly done without disturbing the main lock mechanism in the slightest and without even opening the door on which the lock is mounted.

In the present invention, the knob and knob shank construction are such that the knob, or a portion thereof, may be detached from the shank without disturbing the position of the latter, whereby, when this is done, an entirely new cylinder lock element may be quickly and easily substituted for the old one.

In the form shown herein the removable knob portion is locked to and unlocked from the balance of the knob by means of a special key, which may be kept by the one in charge of the building containing the offices or apartments.

In the accompanying drawing, which shows my invention in one of its preferred forms—

Fig. 1 is, in the main, a longitudinal section of a knob and associated parts, constructed to embody my invention;

Fig. 2 is an end view of one of the parts;

Fig. 3 is an end view of other parts, partially assembled;

Fig. 4 is an end view of another detail;

Fig. 5 is a section similar to Fig. 1, but showing

certain parts in a different position and also showing a different key from that illustrated in Fig. 1;

Fig. 6 is a detail view in longitudinal section, on a plane at right angles to that of Fig. 5;

Fig. 7 is a perspective view of another detail.

1 represents a knob shank, having a flange 1^a which, in the form shown, constitutes a part of the knob. 2 is the other part of the knob, which is arranged to slide longitudinally onto the part 1^a, forming a cavity therein, in which is located a cylinder lock 3, the outer end of the cylinder lock being accessible at the central outer end of the knob, so that a key 4 may be inserted to operate the pin tumblers, whereby the plug 5 of the cylinder lock may be turned to rotate the usual spindle 6, secured to the inner end of the plug, in any suitable manner and by which any appropriate lock and/or latch mechanism (not shown) may be actuated. The knob shank is, of course, borne in its usual manner in any suitable lock mechanism, the construction of which is not essential to this invention, and hence is not shown. It will be observed that the key 4 operates all the pin tumblers excepting the innermost one, this latter being employed for a special purpose. When the key 4 is in place the plug 5 may be turned to rotate the spindle 6.

7—7 are two posts or studs, which are mounted within the knob section 2, while within the section 1^a there are two bores or cavities, indicated at 8—8, designed to snugly receive the studs 7—7. Each stud 7—7 is notched or annularly grooved, as best seen in Fig. 6, at 9, so as to form a locking shoulder, whereby when the knob sections 1^a—2 are fully seated, a locking device may be actuated to engage in the notch portions 9 of the studs 7, so as to prevent the separation of the knob portions 1^a—2. In the form shown herein this locking means comprises a plate 10, having a hub sleeve 11 for receiving the inner end of the plug 5. This locking plate has what I may term two locking ears 10^a—10^b (Fig. 7), and when the plate 10 stands in the position shown in Figs.

3 and 6, it will be seen that these ears 10^a—10^b extend into the bores 8—8, so that they will correspondingly extend into the notches 9 of the plugs 7 when the knob sections 1^a—2 are fully assembled. The hub of the locking plate 11 is preferably provided with an angular passage, the sides of which coact with one or more angular portions on the sleeve 12.

12 is a sleeve, which is rotatably mounted on the inner end of the plug 5, and this sleeve has a squared portion, as shown in Fig. 4, adapted to

50

55

fit into the angular passage in the hub 11 of the locking plate. The innermost pin tumbler and its follower, indicated at 14, are intended to normally unlock the sleeve 12 from the plug 5 and to lock it to the cylinder, so that it will not turn with the plug when the latter is turned by the ordinary pass key 4, for the purpose of turning the spindle 6. When, however, it is desired to operate the locking plate 10, a different key 15 is employed, which will operate all the tumblers, so as to not only release the plug 5, whereby it may be turned in the cylinder, but so that it will lock the sleeve 12 to the plug and unlock it from the cylinder, whereby the sleeve 12 will be caused to turn with the plug. Since the locking plate 10 is mounted on the sleeve 12, it follows that by the use of the longer key 15 the said locking plate may be rotated sufficiently to disconnect the locking ears 10^a from the studs 7-7, thus unlocking the outer portion 2 of the knob, so that the latter may be withdrawn from the part 1^a of the knob, which, of course, opens up the knob so that the cylinder lock mechanism may be easily removed from its support, and another cylinder lock mechanism, adapted to be operated only by a different pass key, may be substituted for the first one. As is usual, the pin housing 3^a of the cylinder lock may be held within the knob in any suitable way, as by means of the usual lugs 16-16, between which it normally rests. 10^b is merely a stop plate, which may be screwed, or otherwise secured, to the plate 10, the purpose being to limit the rotative motion of said locking plate.

Now, summarizing as to the aforesaid construction and its operation, it will be seen that when the parts are assembled, as shown in Fig. 1, the spindle 6 may be turned by an appropriate pass key 4. When it is desired to change the cylinder lock for any reason, so that a different pass key will be required to operate the spindle 6, it is necessary for the one in charge of the building to merely use a special master key, such as indicated at 15. When this is inserted into the lock, as shown in Fig. 5, it serves to move all of the various pins so that the sleeve 12 will be locked to the plug and freed from the cylinder. Then, by turning the key 15, the plug, with the sleeve 12, will turn so that the locking plate 10 may be backed off to a position wherein the locking ears 10^a-10^a disengage the studs 7-7. The outer section 2 of the knob may then be pulled outwardly in a longitudinal direction. Then, by removing the key 15, the cylinder lock may be removed and another one substituted, designed to be operated by a different pass key, although, of course, still being operable by the special master key 15.

When the new cylinder is applied it is first slipped into place in the part 1^a and the outer knob section 2 is then applied, but it will not go fully into place until the special master key is inserted and backed off sufficiently to allow the angular portion of the sleeve 12 to slip into the angular passage of the then backed off locking plate 10. When this occurs the knob slips fully into place and then, by turning the special master key 15 in a clockwise direction, the locking ears 10^a are engaged with the studs 7 and the two parts of the knob are locked together with the new lock held firmly in place, ready to be operated by an appropriate pass key.

While I have shown and described herein a key-controlled device of the pin cylinder type, in which a flat key is employed, my invention is

not necessarily limited to that specific form of lock, as other types might be employed, the main purpose being to provide in the construction of this lock a key-controlled device within a hollow knob, accessible through the outer end of the knob, whereby, by the use of one key, the lock mechanism, such as the spindle 6, may be operated under normal conditions, and whereby by the use of another key insertible into said device the knob locking mechanism may be actuated so that the knob may be separated to permit the key-controlled device to be changed or repaired, as desired.

I claim:

1. In a lock, a knob formed in two separable parts, one part having a shank to be mounted on a door, a cylinder lock within said knob, and means for locking and unlocking the parts of said knob, and said means being positively controlled by said cylinder lock, for securing the knob parts together to hold said cylinder lock in place.

2. In a lock, a knob, said knob being formed in two separable parts, a key-controlled locking device within said knob, including a rotatable element, and means within said knob for locking the parts of said knob together for holding said locking device therein, said locking means being operable by said key-controlled locking device.

3. In a lock, a knob having a shank to be secured to a door, said knob being formed in two separable parts, a cylinder lock in said knob, a plug therein, and means actuated by said plug for locking the parts of said knob together.

4. In a lock, a knob having a shank to be secured to a door, said knob being formed in two separable parts, a cylinder lock in said knob, a plug therein, and means actuated by said plug for locking the parts of said knob together and for also unlocking the same.

5. In a lock, a knob having a shank to be secured to a door, said knob being formed in two parts separable relatively to each other in a direction longitudinal of said shank, a cylinder lock within said knob and supported between said separable parts thereof, a plug therein, one of said knob parts having a locking abutment thereon, and means actuated by said plug for engaging said locking abutment to lock the parts of said knob together.

6. In a lock, a knob having a shank to be secured to a door, said knob being formed in two relatively separable parts, one of said parts having locking abutments and the other of said parts having means for receiving said locking abutments, a cylinder lock within said knob, a plug therein, and a locking member operable by said plug for engaging said locking abutments for locking the parts of said knob together for holding said cylinder therein.

7. In a lock, a knob having a shank to be secured to a door, said knob being formed in two relatively separable parts, a cylinder lock in said knob, a plug therein, said plug being formed in two relatively movable parts locked together, said parts being freed by a key, whereby said plug parts may be rotated relatively to each other, and means actuated by one of the relatively movable parts of said plug for locking the parts of said knob together for holding said cylinder therein.

8. In a lock, a hollow knob formed of two separable parts, a rotatable key operable device detachably mounted within said knob and including a rotatable part accessible for a key at the outer end of said knob, and means for locking

together the separable parts of said knob, said rotatable part coacting positively therewith to move said knob locking means to both lock and unlock said separable knob parts.

- 5 9. In a lock, a hollow knob formed of two separable parts, a rotatable key operable device detachably mounted within said knob and including a rotatable part accessible for a key at the outer end of said knob, and means for locking together the separable parts of said knob, said rotatable part coacting positively therewith to engage and disengage said knob locking means when one key is used, whereby said knob parts may be locked together or separated, said rotatable part being operable by a different key for a different purpose.

- 10 10. A hollow door knob, including two separable parts, locking means within the knob for engaging and disengaging said parts, and key operable means inside of said knob for operating a door locking means under one condition and for operating the knob locking means under another condition.

- 15 11. A hollow door knob, including two separable parts, means for engaging said parts by a longitudinal movement of one relatively to the other, knob locking means within the knob to prevent longitudinal motion of the parts when assembled, door lock operating means also associated with said knob, and key-controlled means also within said knob and operable by one key to operate the door lock operating means and by another key to operate the knob locking means, said knob locking means including a movable piece carried by one of the knob parts and engageable with and disengageable from the other knob part.

- 20 12. A hollow door knob, including two separable parts, means for causing said parts to be engageable and disengageable by a substantially longitudinal motion of one relatively to the other, knob locking means within the knob to prevent said longitudinal motion of said parts when assembled, door lock operating means associated with said knob, and key controlled means also 25 within said knob and operable by one key to op-

erate the door lock operating means and by another key to operate the knob locking means.

13. A hollow door knob, including two separable parts, means for causing said parts to be engageable and disengageable by a substantially longitudinal movement of one relatively to the other, knob locking means within said knob to prevent said longitudinal movement of said knob parts when assembled, door lock operating means also associated with said knob, and key controlled 10 means within said knob, operable under one condition to operate the door lock operating means and under another condition to operate the knob locking means.

14. In a lock, a two-part separable knob, a lock mounted therein, means for locking the two parts of said knob together against separation, key controlled means to operate said knob locking means by the rotation of said key in said lock.

15. A hollow knob including two separable parts 20 to permit a key operable lock mechanism to be inserted into and removed from the interior of said knob, means for locking said knob parts together against separation, and means movable by said lock mechanism and coacting with the 25 means for locking said knob parts to operate the latter in one direction.

16. A hollow knob including two separable parts to permit a key operable lock mechanism to be inserted into and removed from the interior 30 of said knob, means for locking said knob parts together against separation, and means movable by said lock mechanism and coacting with the means for locking said knob parts to operate the latter in both directions. 35

17. In a device of the character described, a cylinder lock including a rotatable plug, a support formed of a plurality of interengaging parts for enclosing the cylinder but exposing the outer end of its plug, locking means for said interengaging parts, means actuated by said plug for moving said locking means to and fro to lock and unlock said interengaging parts. 40
